UNITED STATES PATENT OFFICE

2,522,777

CAN OPENER

Noah A. Butt and William Clyde Byrd,
Atlanta, Ga.

Application October 29, 1946, Serial No. 706,410

5 Claims. (Cl. 30—16)

1

This invention relates to a novel device for opening metallic containers and is essentially applicable to liquid containers.

An object of this device is to provide means for cutting an aperture in the top of a container and preventing any metal from falling into the container.

Another object of this invention is to provide a device whereby a plug may be taken out of a container and held in the device by which it is removed and may be expeditiously removed therefrom, all in accordance with the volition of the operator.

A further object of this device is the provision of a novel, efficient and inexpensive means for satisfactorily opening liquid containing receptacles, without leaving rough edges about the opening.

Other objects and features of novelty of this invention will be specifically pointed out or will become apparent when referring, for better understanding of the invention, through the following description taken in conjunction with the accompanying drawing, wherein:

Figure 1 is a perspective view of this invention showing the receptacle opener, the receptacle and a plug especially adapted to close the smooth aperture made by the use of this invention; and,

Figure 2 is a longitudinal section of the invention showing the construction thereof, parts being shown in elevation.

Referring now to a more detailed description of the drawings wherein like reference characters indicate similar parts in the views of the invention, 10 indicates in a general way a preferred embodiment of this inventive concept.

Taking now Figure 2 a handle 12 made of any suitable material such as wood, light metal, plastic or the like is provided with a knurled grip portion 14 at one end thereof. Extending longitudinally in the handle 12 is a bore 16 which receives a metallic sleeve 18. The sleeve 18 is provided with two co-axial bores therein of different diameters, the larger indicated at 20 communicating with the smaller indicated at 22. Slidably secured in the larger and smaller bores of sleeve 18 is a piston or plunger 24 having a larger diameter 26 and a smaller diameter 28 adapted to be received in the larger bore 20 and the smaller bore 22 respectively. Extending from and forming a continuation of sleeve 18 is a pair of blades 30 and 32 preferably of laterally arcuate shape as shown. The said blades are bevel ground on the outside edges so that in piercing a container the edges of the aperture resulting

2

from piercing the said container will be conveniently turned downward in order to obviate the undesirable rough edges usually encountered in such cuts.

5 The operation of this invention is as follows. A container, preferably a liquid container, generally indicated at 34, is pierced by the knife edges 30 and 32 which may be beveled on either the front, the back or both edges thereof. It is here noted that the conjunction of the said knife blades with the said sleeve is formed an abutting shoulder 36 adapted for engagement with the top portion of the container to be cut or opened for limiting the penetration of the device into the said container 34. After the invention has pierced the container to be opened it is turned approximately one-quarter of a revolution cutting a small disk 38 out of the top of the container. This disk is retained in the blades by frictional engagement thereof and is removed by shaking the invention causing the piston or plunger 24 to reciprocate in the sleeve 18 thus knocking out the undesired portion of the container.

10 15 20 25

It is here noted that since a uniform cut is taken in all containers a stopper 40 is provided for use with the invention since stoppers may be manufactured of a certain size to suit the size aperture made by the particular embodiment of the present invention which is used.

30 35 While there is described and illustrated a preferred embodiment of the instant invention, it will be apparent to those skilled in the art that various changes including omissions and additions may be made herein without departing from the spirit and scope of this invention as set forth in the accompanying claims.

While the grip portion is shown round and tapered to suit the hand, it is noted that the said grip portion might be of any other convenient configuration. It is also noted that instead of a knurled grip portion as shown at 14, this invention contemplates the use of a corrugated grip or grooved grip or, if desired, the entire handle might be figured with anti-slip means.

40 45 50 55 It is noted here that a tapered slot is provided between the blades 30 and 32, the function of which is apparent. When the blades have penetrated their full depth, a small portion of the can is left uncut, the cut being completed by turning the device about a quarter of a turn as hereinbefore mentioned. The shape of the slot in cooperation with the knife blades retains the cut out disk by the rough edges that are left on the disk after

the final shearing operation takes place for later removal from the invention as described.

Having thus described this invention, what is claimed is as follows:

1. In an opener for liquid containers, a handle, a sleeve extending longitudinally therein and protruding from one end thereof, a pair of blades forming a continuation of said sleeve and resiliently inclined towards each other, a container abutting ridge at the junction of said blades and sleeve, and a plunger inertia member freely floating and confined within said sleeve, whereby a cut-out portion of a container may be removed from the opener after extracting the same from the said container.

2. A device for opening containers comprising a handle having an axial bore therein, a sleeve in the said bore and extending therefrom, said sleeve having a larger and smaller bore therein, a plunger having a larger and smaller diameter portion freely slidably in the said bores of the said sleeve, a plurality of blades extending from and forming a continuation of said sleeve being inclined towards each other, said blades being adapted to pierce, cut and retain a portion of a container and said plunger protruding between said blades to knock out the portion of container retained in said knife blades.

3. A device for forming an opening in a container, retaining the resultant plug and discarding the retained plug, said device comprising a sleeve having a bore, a counterbore in said sleeve, an inertia member having an enlargement disposed in said counterbore, said member being floatingly received in said bore and counterbore, cutting blades forming a continuation of said sleeve and being inclined toward each other in order to cut a plug from the container and retain the plug, and said floating inertia member being slidably received between a portion of said cutting blades in order to forcibly eject the plug therefrom upon reciprocation of the sleeve.

4. A device for forming an opening in a container, retaining the resultant plug and discarding the retained plug, said device comprising a

10
15

sleeve having a bore, a counterbore in said sleeve, an inertia member having an enlargement disposed in said counterbore, said member being floatingly disposed in said bore and counterbore, cutting blades forming a continuation of said sleeve and being inclined toward each other in order to cut a plug from the container and retain the plug, said floating inertia member being slidably received between a portion of said cutting blades in order to forcibly eject the plug therefrom upon reciprocation of the sleeve, and a shoulder formed at the junction of said cutting blades and said sleeve for limiting the travel of the sleeve within the container upon removal of a portion of the container.

35

5. A device for forming an opening in a container, retaining the resultant plug and discarding the retained plug, said device comprising a sleeve having a bore, a counterbore in said sleeve, an inertia member having an enlargement disposed in said counterbore, said member being floatingly received in said bore and counterbore, cutting blades forming a continuation of said sleeve and being inclined toward each other in order to cut a plug from the container and retain the plug, said floating inertia member being slidably received between a portion of said cutting blades in order to forcibly eject the plug therefrom upon reciprocation of the sleeve, a shoulder formed at the junction of said cutting blades and said sleeve for limiting the travel of the sleeve within the container upon removal of a portion of the container, and, said cutting blades being resiliently biased toward each other.
